CLAIM

The ornamental design for a handle for a crate for bottles or the like, as shown and described.

DESCRIPTION

FIG. 1 is a perspective view of our new design for a handle for a crate for bottles or the like. The crate is shown in broken lines and forms no part of the claimed design;

FIG. 2 is a top plan view thereof at an enlarged scale;

FIG. 3 is a front elevational view thereof at an enlarged scale, the rear elevational view being a mirror image thereof;

FIG. 4 is a left side elevational view thereof at an enlarged scale, the right side elevational view being a mirror image thereof; and,

FIG. 5 is a bottom plan view thereof at an enlarged scale.
